UNITED STATES PATENT OFFICE

154,703

DESIGN FOR A PORTABLE ELECTRIC FAN

Leonard R. Phillips, Teaneck, N. J., assignor to
Anemostat Corporation of America, New York,
N. Y., a corporation of Delaware

Application April 29, 1948, Serial No. 146,029

Term of patent 14 years

(Cl. D26—7)

To all whom it may concern:

Be known that I, Leonard R. Phillips, a citizen of the United States, residing at Teaneck, in the county of Bergen and State of New Jersey, have invented a new, original, and ornamental Design for a Portable Electric Fan, of which the following is a specification, reference being had to the accompanying drawing, forming part thereof;

Fig. 1 is a side elevation of a portable electric fan, showing my new design

Fig. 2 is a front elevation thereof.

Fig. 3 is a top plan view thereof; and

Fig. 4 is a rear elevation thereof.

I claim:

The ornamental design for a portable electric fan, substantially as shown.

LEONARD R. PHILLIPS.
